MOUNT FOR PRECIOUS STONES

Adolf Herman Hess, 7411-1B Yonge St., Apt. 508,
Thornhill, Ontario, Canada

Filed Sept. 21, 1972, Ser. No. 290,855

Term of patent 14 years

Int. Cl. D11—01

U.S. Cl. D45—1 B

FIG. 1

FIG. 2

FIG. 1 is a perspective view of a mount for precious stones showing my new design, taken obliquely from above; and

FIG. 2 is a perspective view of the mount of FIG. 1, taken obliquely from below.

FIG. 3 is a top plan view.

I claim:

The ornamental design for a mount for precious stones, as shown and described.
